ROTARY POWER-REVERSING MECHANISM

John B. Picard, Toledo, Ohio, Bruno R. Schabarum, Tulsa, Okla., and George F. Noltein, Springfield, Ohio, assignors to The National-Superior Company, Toledo, Ohio, a corporation of Delaware

Original application March 17, 1934, Serial No. 716,130. Divided and this application February 19, 1935, Serial No. 7,322

5 Claims. (Cl. 74—205)

This invention relates generally to reversing mechanism for transmitting rotary power in either direction and more particularly to a unitary reversing mechanism which may be interposed between the source and the application of the power transmitted.

This application is a division of application Serial No. 716,130, filed March 17, 1934.

The invention may be conveniently applied, for example, to countershaft reversing mechanism adapted for quickly and smoothly changing the direction of the applied motion without interrupting the motion at the source of power.

As herein illustrated this invention is shown applied to a reversing countershaft mechanism for use with apparatus in the process of producing oil from wells.

Hoisting reels or drums are employed intermittently for relatively short intervals from the commencement of the drilling of a well until the well is producing or abandoned. The hoisting reels are generally driven by any suitable source of power through power transmitting means and it is necessary that these reels be reversed without reversing the direction of rotation of the power-driving source. However, the use of rotary power, capable of function in either direction, is not in any manner restricted to hoisting mechanism during the process of producing oil from the earth.

The reversing mechanism, as herein illustrated, is required to perform heavy duty service in reversing the direction of rotation of the mechanism under heavy loads at high speeds. In order to avoid casualties in the work as well as among the workers, reversing mechanism must operate quickly and smoothly and without loss of time. Time is of the essence of some of the operations in performing this type of work as the operation may be lost and have to be repeated because its sequence was broken in time.

Another requirement of a countershaft reversing mechanism is that it may be adaptable for use in combination with any of several types of power source units without changes or additions to said power source units.

To these ends this invention provides novel features in the transmission means for smoothly reversing the direction of rotation of the power delivered by the mechanism and in the arrangement for supporting the power in-put and power out-put means in axial alignment and in the means for operating the reversing mechanism.

The accompanying drawings illustrate, for purposes of exemplification but without limitation of the claimed invention thereto, certain practical embodiments of the principles of this invention.

Fig. 1 is a plan view of the reversing mechanism, parts of which are in section and parts of which are broken away.

Fig. 2 is a plan view showing the base of the

mechanism with the lever and link system for operating the forward and reversing means of the device.

Fig. 3 is an end view of the reversing mechanism.

Fig. 4 is a detailed view partly in section of a form of the forward drive clutch mechanism.

Referring to the drawings and more particularly to Figs. 1 to 4, 10 represents the base or frame structure having secured on its ends the upright bearing stands 11 for supporting the main bearing housings 12, which may be fastened thereto as by the bolts 13. 14 represents a rotary shaft journaled within the bearing housings 12.

15 represents a universal joint arranged to connect the right hand end of the shaft 14 directly to the shaft 16. The shaft 16 has attached thereto the fly-wheel 17, as indicated in Fig. 1, and represents the source of rotary power for the mechanism.

20 23 represents a rotary gear or pulley member which is secured to the shaft 14 by means of a key 18. 24 represents a rotary driving sleeve member which is carried by the sleeve bearings 25 mounted for rotation on the shaft 14. The outer 25 ends of the sleeve bearings 25 are provided with the flanges 26 arranged to be engaged by the ends of the sleeve member 24 on one side and the collar 27 and the hub of the rotary gear or pulley member 23 one the other side, which engagement 30 prevents any axial movement of the sleeve 24 on the shaft 14.

The member 23 has secured thereto the cylindrical drum 31 provided with a smooth perimetral friction surface which is encircled by the half 35 clutch bands 32 and 33.

One end of the clutch bands is provided with the strap 34 having a transverse cylindrical sleeve arranged to be pivotally mounted on the pin 35 extending from the face of the crank disc 36 on the 40 inner end of the shaft 37 which is rotatably mounted in the conical or reverse friction drum member 38. The other end of the clutch bands is provided with a pierced lug 39 arranged to receive the threaded portion of the bolt 40 which is 45 adjustably secured thereto as by the nuts and lock nuts 41. The bolt 40 is also provided with a transverse cylindrical sleeve arranged to be pivotally mounted on the pin 42 extending from the face of the crank disc 36 on the inner end of the shaft 37. The outer ends of the pins 35 and 42 are held in place by the cap disc 36'.

The shafts 37 are parallel to each other and symmetrically disposed on either side of the axis 55 of the drum 38 and parallel to the latter. The center of the pins 35 and 42 are eccentric to the axis of the shafts 37, as shown in Fig. 4, and when the shafts 37 are rotated the pins move the straps 34 and the bolts 40 clamping or re- 60

leaving the bands in frictional engagement with the cylindrical drum 31.

If the shafts 37 are rotated so as to clamp the bands onto the drum 31, the rotary pulley 23 then drives the conical drum 38 in the same direction through the clutch band mechanism and the shafts 37.

The conical drum 38 is secured to the shaft sleeve 24. The driving gear or pulley member 45 is also keyed to the sleeve 24 by the key 46 which is locked in place by the set screws 47. Thus any rotary movement imparted to the conical drum 38 drives the driven pulley 45 through the medium of the shaft sleeve 24.

15 48 represents a clutch operating sleeve splined as at 49 on the shaft sleeve 24 to permit longitudinal motion of the clutch sleeve thereon. The sleeve 48 is provided with a pair of sockets 50 to receive the ball joints 51 on one end of the connecting links 52.

The ball joints 53 on the other end of the connecting links 52 are arranged to be secured in their complementary sockets 54 in the lever arms 55, secured to the outer ends of the shafts

25 37. The clutch operating sleeve 48 is provided with the integral annular key 56 arranged to rotate in the annular groove of the stationary partible collar 57.

The collar 57 is provided with two outwardly extending and oppositely disposed ears 58 arranged to extend into the slots 59 in the ends of the bifurcated lever 60 which is pivotally supported in the stand 61 secured to the frame 10 as shown in Figs. 1, 2, and 3.

35 Thus when the lever 60 is moved in a counterclockwise direction it carries with it the collar 57 which in turn slides the rotating clutch sleeve 48 to the left and longitudinally of the shaft sleeve 24. The links 52 then rotate the levers 40 55 and the shafts 37 in a counterclockwise direction in Fig. 4, causing the pins 35 and 42 to pull the clutch bands into frictional engagement with the cylindrical drum 31, thereby rotating the shaft sleeve 24 and the driving pulley 45 therewith. This is termed the direct or forward drive of the mechanism. The sleeve shaft 24 and the sleeve bearings 25 will in this instance rotate in the same direction and at the same speed as the shaft 14.

50 Conversely, movement of the bifurcated lever 60 in a clockwise direction will disengage the clutch bands from the drum 31.

As herein illustrated the reverse drive of the mechanism is attained by the use of the frusto-conical rollers 62 which in this case performs the dual function of a clutch and a gear element for reversing the mechanism.

63 represents a frusto-conical face on one side of the driven pulley 23 adjacent the periphery thereof which is, in this instance, provided with the frictional lagging material 64 arranged to engage the conical surface of the rollers 62.

65 The rollers 62 may be composed of laminated material to insure long and uniform wearing qualities well known in the friction pulley art. 65 represents the conical surface of the drum 38 which is also arranged to be engaged by the rollers 62. Thus the rotary driven pulley 23 may be made to drive the drum 38 and the driving pulley 45 on the shaft sleeve 24 in the reverse direction when the frusto-conical rollers 62 are moved into engagement with the conical frictional surfaces on the pulley 23 and the drum 38.

75 The rollers 62 are rotatably supported by the anti-frictional bearings 66 on the non-rotary

spindle 67 whose axes are in this instance disposed at an angle substantially 45 degrees to the shaft 14 and in the same horizontal plane.

68 represents a cap plate on the inner end of the spindle 67 arranged to hold the inner races 5 of the bearings 66 and the spacing sleeve 69 against the shoulder 71 on the shaft. 70 represents a hub-cap arranged to close the bore of the inner face of the rollers 62 to prevent dirt and other foreign matter from entering therein. 10

From the shoulders 71 to the shoulders 72 the spindles are cylindrical and from the shoulders 72 the outer ends of the spindles are square in cross section as shown in Figs. 1 and 3 at 15 73. The square end portion of each spindle is slidably supported in the upwardly open squared bearing slot 74 in the bearing box 75 carried by the upright stand 76 whose lower ends are secured to the base frame 10. The bearing slot 74 is arranged to be closed at the top by the plate 77 20 bolted to the bearing box. The slot 74 is wider than the squared portion of the spindle, permitting it to move transversely therein.

78 represents helical springs carried within suitable openings 79 in the vertical face, of the 25 squared portion 73 of the spindle, that is remote from the driven pulley 23. The ends of the springs are provided with the mushroom headed pins 80 whose outer faces bear against the vertical wall 81 of the slot 74.

30 The pressure of the springs acts on the pins 80 to move the spindle 67 away from the vertical wall 81. The transverse movement of the spindle 67 is limited by the plates 82 on the ends of the adjusting bolts 83 which pass through tapped 35 holes in the wall of the bearing housing 75.

Thus when the spindle 67 is moved inwardly to engage the roller 62 with the conical friction surfaces, the roller first contacts the frictional driving surfaces 64 of the rotary pulley 23 and is thereby rotated. Further inward movement of the spindle 67 forces the rotating roller 62 up the conical surface 64 moving the axis of the spindle transversely of the bearing and compressing the springs 78 until the roller engages the conical friction surface 65 on the drum 38, thereby driving the shaft sleeve 24 and the driving pulley 45 in the reverse direction as long as the rollers are thus held in engagement with their complementary frictional surfaces. 50 When the rollers 62 are in their full meshed position and conical friction surfaces extend to form a complete cone they would meet at an apex on the axis of the shaft 14 which precludes any possibility of sliding friction between the 55 faces of the contacting elements.

The spindles 67 are moved longitudinally of their axis by means of the vertical levers 84 pivotally supported at 85 on the stands 76. The upper ends 86 of the levers 84 are bifurcated 60 to fit around the spools 87 adjustably secured to the ends of the squared portion 73 of the spindles. The lower ends of the levers 84 are pivotally attached to the adjustable connecting rods 88 which extend through the guides 89 and 65 are pivotally attached at their other ends to the bell cranks 90 pivoted to a bracket on the cross member of the base 10 as shown in Fig. 2.

70 The other ends of the bell cranks are connected by the short links 91 to the cross pin 92 which is supported by the lower bifurcated end 93 of the forward clutch lever 60. The trifurcated head 94 on the end of the link 95 is provided with alined holes to receive the pin 92 75 and is arranged so that its center fork is be-

tween the bifurcated ends of the lever 60. The links 91 are outwardly adjacent thereto and the outer forks of the head 94 are on the ends of the pin as shown in dotted lines in Fig. 1.

5. The other end of the link 95 is pivotally attached to the bell crank 96 pivoted at 97 on the frame 10 and having its other end connected by the rod 98 to the hand operating lever 99.

When the lever 99 is moved to the left, as in Fig. 3, the forward clutch lever 60 will be operated in a clockwise direction disconnecting the forward clutch drive and at the same time the bell crank 96 will be operated in a counter-clockwise wirection in Fig. 2, thereby rocking the reverse lever 84 to move the rollers 62 into engagement with their complementary faces to operate the driving pulley 45 in the reverse direction. When the hand operating lever is in its neutral position the linkage system is arranged to permit the driven pulley 23 to rotate alone.

Referring to Figs. 1 and 3, 100 represents a brake drum secured to the shaft sleeve 24 by the key 101. The perimetral surface of the brake drum is grooved to receive the brake band 102 supported from below on the pin hinge 103 secured in the bracket 104 bolted to the cross member 105 of the bearing stand 11. The brake is operated by the ordinary brake rod 106 and cammed lever 107 arranged, when pulled to the right in Fig. 3, to shorten the bolt 108 to draw the ends 109 of the band together, gripping the drum to slacken the speed or stop the rotation of the driving pulley 45.

Owing to the fact that the shaft 14 is designed to rotate, antifrictional roller bearings cannot be used as they would be stationary relative to the rotating shaft and shaft sleeve 24 and their line contact would be into the races ultimately causing their destruction. It is therefore necessary to use the sleeve type of bearing 25 for rotatably supporting the drive shaft sleeve 24 to avoid this difficulty.

While this invention has been illustrated and described particularly in reference to a countershaft reversing mechanism for use with well drilling and pumping apparatus, it should be understood that changes may be made in the form disclosed, without departing from the spirit of the invention and that certain features may sometimes be used to advantage without a corresponding use of other features.

We claim:—

1. In a rotary reversing mechanism, the combination of a rotary shaft, a member fixed thereon and having on its one face a conical driving surface and concentric therewith a cylindrical driving surface, a member to be driven rotatably mounted on the shaft adjacent to said face of the first member, said second member being provided with a conical surface opposed to the conical driving surface of the first member and also provided with clutch bands arranged to be tightened about the cylindrical driving surface of the first member whereby to rotate the second member in unison with the shaft, and means arranged to be interposed between the conical surfaces of both members whereby to rotate the second member in the opposite direction.

2. In a rotary reversing mechanism, the combination of a rotary shaft, a member fixed thereon and having on its one face a conical driving surface and concentric therewith a cylindrical

driving surface, a member to be driven rotatably mounted on the shaft adjacent to said face of the first member, said second member being provided with a conical surface opposed to the conical driving surface of the first member and also provided with clutch bands arranged to be tightened about the cylindrical driving surface of the first member whereby to rotate the second member in unison with the shaft, and means arranged to be interposed between the conical surfaces of both members whereby to rotate the second member in the opposite direction said last mentioned means being arranged to first engage the conical driving surface of the first member.

3. In a rotary reversing mechanism, the combination of a rotary shaft, a member fixed thereon and having a conical driving surface and concentric therewith a cylindrical driving surface, a member to be driven rotatably mounted on the shaft adjacent the first member, said second member being provided with a conical surface opposed to the conical driving surface of the first member and also provided with clutch bands arranged to be tightened about the cylindrical driving surface of the first member whereby to rotate the second member in unison with the shaft, and means supported independently of the shaft arranged to be interposed between the conical surfaces of both members whereby to rotate the second member in opposite direction.

4. In a rotary reversing mechanism, the combination of a rotary shaft, a member fixed thereon and having a conical driving surface and concentric therewith a cylindrical driving surface, a member to be driven rotatably mounted on the shaft adjacent the first member, said second member being provided with a conical surface opposed to the conical driving surface of the first member and also provided with clutch bands arranged to be tightened about the cylindrical driving surface of the first member whereby to rotate the second member in unison with the shaft, supports at opposite sides of the shaft, and frusto-conical rollers journaled on said supports and arranged for axial movement, said rollers arranged to be interposed between said conical surfaces to rotate the second member in the opposite direction.

5. In a rotary reversing mechanism, the combination of a rotary driven shaft, a member fixed to said shaft, a second member rotatably mounted on said shaft and having a conical driven surface, a cylindrical driving surface and a conical driving surface on the side of the first member adjacent the second member, band members carried by the second member and arranged when operated to engage the cylindrical driving surface for rotating the second member in the same direction as that of the shaft, means on said second member arranged when rotated to clamp the band members into frictional engagement with the cylindrical driving surface, independent means arranged to first engage the conical driving surface and then engage the conical driven surface to rotate the second member in the opposite direction from that of the shaft, and means for alternately operating both of said aforementioned means.
